UNITED STATES PATENT OFFICE

ALEXANDER A. SKVORTZOFF, OF SHARON, PENNSYLVANIA, ASSIGNOR TO WESTINGHOUSE ELECTRIC & MANUFACTURING COMPANY, A CORPORATION OF PENNSYLVANIA

BUSHING STRUCTURE

Application filed December 14, 1928. Serial No. 326,013.

My invention relates to electrical-bushing structures and particularly to bushing structures of the high-voltage type.

An object of my invention is to provide a bushing of the above-indicated character that shall be tightly sealed against the passage of fluids, such as air, oil and any other medium which it is desired to use and which flows.

Another object of my invention is to provide a bushing that shall permit relative movement between sealed parts thereof without adversely effecting the seal between such parts.

Another object of my invention is to provide a bushing structure that shall permit the ready testing of the fluid-tight sealing parts without materially altering the structure, as it would exist without the testing means.

A further object of my invention is to provide a high-voltage-bushing structure that shall be simple and durable in construction, economical to manufacture and effective in its operation.

In electrical bushings, particularly those of the high-voltage type, it is desirable to have the same as nearly perfectly sealed as possible against the admission of moisture and the egress of oil or other insulating fluid.

Many suggested means, including screw caps, gaskets and other devices, have been employed in bushings of this character with some degree of success, but the problem is still of sufficient importance to cause a great deal of constructive effort to solve it completely, not only from the standpoint of absolute fluid tightness, but also from the viewpoints of commercial and engineering expediency and economy.

It has recently been suggested, in bushing structures embodying inorganic insulating material, such as porcelain, to provide a metallic-glaze surface on a portion of the porcelain, whereby a substantially perfect hermetic seal may be effected. However, this expedient has certain defects, as do most seals that have been heretofore suggested. One of the objections to this expedient is the necessity for refiring the porcelain, after it has been originally fired in the kiln, to provide the metallic-glaze surface.

It is my aim to provide a hermetically-tight seal that shall be substantially as perfect as one employing the metallic glaze above-mentioned and that shall have advantages over other expedients of the prior art.

Accordingly, in practicing my invention, I provide a bushing in which a flexible metallic member is so homogeneously sealed in position between the bushing conductors and a metal end cap therefor, and in which the metal end cap is so mechanically sealed to the end of the tubular member as to provide a substantially perfect seal in what is believed to be a more simple economical and expeditious manner than in any similar bushing structure heretofore employed.

The single figure of the accompanying drawing is a side view, partially in elevation and partially in section, of a portion of a bushing structure constructed in accordance with my invention.

The device comprises, in general, a tubular dielectric member 2, a conductor 3 extending longitudinally therethrough, a holding member 4 on the member 2, a sealing gasket 5, a cap or closure member 6 and a flexible sealing element 7 between the conductor 3 and the cap 6.

The dielectric member 2, only the upper end of which is shown, is preferably constructed of porcelain having a flat-plane outer surface 9 and annular surface-creepage flanges (not shown) distributed along its outer side, in a usual and well-known manner.

The conductor 3, which may be tubular or solid, as illustrated, and extended entirely through the lower part of the bushing structure (not shown), may also be provided, within the tubular member 2, with a condenser bushing of a well-known type. Also, a body 8 of oil or other insulating medium may be provided in the member 2.

The holding member 4, preferably of metal and of closed loop or ring-like character having tapped openings 12 about its outer end surface for the reception of screw bolts 14 for holding the ring 6 in position, is also preferably displaced slightly inwardly from the end surface 9. The ring 4 may be secured or

bonded to the tubular member 2 in any manner, permanently and tightly securing the ring in position, as by a body of cement 15, alloy or other suitable means.

5 The sealing gasket 5, preferably of cork, hard rubber or similar yielding material, is also preferably initially treated with a sealing substance, such as bakelite varnish or other suitable material, which is applied to 10 both sides of the gasket.

The cap 6, preferably of copper or brass, is of substantially flat-plane discoidal or ring-like character having perimetral openings 16 for the reception of the bolts 14, a central 15 opening 17, through which the conductor 3 loosely extends in spaced relation thereto, and a radial opening or duct 18 having a removable closure cap member 19 at the outer end thereof.

20 The flexible sealing element 7, preferably of sheet material, such as copper or soft brass, is of substantially bell-shape having its upper or smaller apertured end 20 sealed in position about the conductor 3, as by a 25 ring of solder 22, and its lower or mouth perimeter sealed to the cap 6 by a sealing ring 23, similar to the ring 22.

The above-described structure embodies a 30 hermetically-tight seal between the conductor 3 and the cap 6, whereby the conductor may move either by thermal expansion of the parts or by mechanical strains relative to the cap and the parts therebeneath.

During assembly, the gasket 5 is placed in 35 the position shown, with the varnish thereon in wet or tacky condition. The cap 6 is mounted in position and screwed down tightly, by means of the bolts 14, to compress the gasket 5 and is held in position by lock washers 24.

The duct 18 is provided to permit the sealed parts to be tested in a simple and expeditious manner by admitting fluid, such as air, under pressure.

45 In the above-described structure, the parts are all of standard well-known materials and construction which are easily and economically manufactured. They may also be readily and expeditiously assembled without special tools or extra equipment and cooperate to provide an extremely effective structure.

50 While I have shown and described a particular form of my invention, changes may be effected therein without departing from the spirit and scope thereof, as set forth in 55 the appended claims.

I claim as my invention:

1. A bushing comprising a dielectric tube, a holding member bonded to, and around, 60 said tube and displaced from an end thereof, a ring over said end having a radial duct, removable means for sealing said duct, a sealing gasket between said end and said ring, a conductor extending through said ring in spaced relation thereto, a flexible sheet-ma-

terial bell surrounding said conductor over said ring having its smaller outer end intimately joined to said conductor and its larger inner end intimately joined to said ring, and means for clamping said holding member relative to said ring to compress said gasket. 70

2. A bushing comprising a tubular insulating structure, a holding member secured thereto adjacent to an end thereof, a ring over said end, a sealing gasket between said end and said ring, a conductor extending through said ring in spaced relation thereto, a flexible sheet-material bell surrounding said conductor over said ring having its smaller outer end intimately joined to said conductor and its larger inner end intimately joined to said ring, and means for clamping said holding member relative to said ring to compress said gasket. 75

80 3. A bushing comprising a tubular insulating structure, a holding member secured thereto adjacent to an end thereof, a ring over said end, a sealing gasket between said end and said ring, a conductor extending loosely through said ring, a flexible sheet-material element surrounding said conductor in intimate joinder to the same and to said ring, and means for clamping said holding member relative to said ring to compress said gasket. 85

90 4. A bushing comprising a tubular insulating structure, a holding member secured thereto, a ring over an end of said structure, a sealing gasket between said end and said ring, bonding material intimately joining and sealing said gasket to said end and to said ring, a conductor extending through said ring to permit movement of the conductor relative thereto, flexible sealing means between the conductor and the ring, and means cooperating between said holding member and said ring to hold the same relative to each other. 95

100 5. A bushing comprising a tubular insulating structure, a ring over an end of said structure, means hermetically sealing said ring to said end, a conductor extending through, and permitted to have movement relative to, said ring, flexible means between, and intimately united to both the conductor and the ring for hermetically sealing the same to each other, and means for securing the tubular structure and the ring to each other. 110

115 6. A bushing comprising a tubular insulating structure, a removable ring over an end thereof, means hermetically sealing said ring to said end, a conductor extending through, and permitted to have movement relative to, said ring and an annular flexible metal element intimately united to the conductor and to the ring. 120

125 7. A bushing comprising a tubular insulating structure, a conductor extending longitudinally through an end thereof and per-

mitted to have movement relative thereto, and means for hermetically sealing the conductor to said structure, including an annular flexible metal element intimately united 5 in sealed relation to the conductor and a removable metal ring-like element intimately united in sealed relation to said flexible element between said element and said end.

8. A bushing comprising a tubular insulating structure, means for hermetically sealing an end thereof including a removable metal ring-like element sealed to said end and an annular flexible metal element intimately united and sealed, to said element, and a 15 conductor disposed longitudinally in said tubular structure and intimately connected, and sealed to said flexible element.

9. In combination, a member having an opening therethrough, an apertured element 20 disposed with its opening opposite the opening in said member, sealing means between said member and said element about an axis through said openings, a member extending loosely through said openings, flexible sealing means about said axis intimately joined to said element and to said loosely-extending member, and means cooperating between said first member and said element to hold the same relative to each other.

25 30 In testimony whereof, I have hereunto subscribed my name this 16th day of November, 1928.

ALEXANDER A. SKVORTZOFF.
